UNITED STATES PATENT OFFICE.

EARL W. DOTTEN, OF AITKIN, MINNESOTA.

POWER-SPUD FOR DREDGES.

1,154,492.

Specification of Letters Patent. Patented Sept. 21, 1915.

Application filed October 26, 1911, Serial No. 656,940. Renewed May 5, 1914. Serial No. 836,558.

To all whom it may concern:

Be it known that I, EARL W. DOTTEN, a citizen of the United States, and a resident of Aitkin, in the county of Aitkin and State 5 of Minnesota, have invented a new and Improved Power-Spud for Dredges, of which the following is a full, clear, and exact description.

The object of the invention is to provide 10 a new and improved power spud for dredges and similar machines, arranged to permit of conveniently and quickly adjusting the spud, to change the position of the dredge or similar machine correspondingly, and to allow 15 of quickly withdrawing the spuds from active positions whenever it is desired to move the machine about from one place to another.

For the purpose mentioned, use is made 20 of a spud made in sections slideable one on the other, and power-driven means for shifting the spud sections one relative to the other.

A practical embodiment of the invention 25 is represented in the accompanying drawings forming a part of this specification, in which similar characters of reference indicate corresponding parts in all the views.

Figure 1 is a front elevation of a power 30 spud in position on a dredge shown in dotted lines, part of the power spud on one side of the machine being in section; Fig. 2 is an enlarged sectional elevation of the power spud on the line 2—2 of Fig. 1; Fig. 3 is an enlarged sectional plan view of the same on 35 the line 3—3 of Fig. 1; and Fig. 4 is a front elevation of a modified form of the driving mechanism.

On the deck of the hull A of the dredge or 40 similar machine is mounted an A-frame or a shear B connected by the usual adjusting cable C with the boom D mounted at its inner end on a turntable E arranged on the hull A, the outer end of the boom D carrying the usual guide rod F and bucket G together with the necessary mechanism for manipulating the bucket in the usual manner.

On opposite sides of the shear B are arranged power spuds H, each consisting of 45 an upper section H' and a lower section H² slidable on the upper section H', preferably by telescoping therein, as plainly indicated in the drawings. The lower end of each lower spud section H² is provided with a pivoted foot I, and the said spud section H² is piv- 50

otally connected by a link J with the corresponding side of the hull A. 55

The under side of each lower spud section H² is provided with a rack K in mesh with a pinion L secured on a shaft L' journaled in suitable bearings N mounted on the upper 60 spud section H', and on the said shaft L' is secured a worm wheel O in mesh with a worm O' mounted to slide on and to turn with a driven shaft P provided with a joint P², and provided preferably with a polygonal outer end P' engaging a correspondingly-shaped bore in the worm O' so that the latter is free to slide on the said polygonal end P' and rotates with the shaft P when the latter is turned. The ends of the 70 worm O' are journaled in the fork of a bearing Q fulcrumed loosely on the shaft L'. 75

It will be understood that since the worm O' turns with and slides on the shaft P, it and the said shaft virtually form an extensible shaft. 80

Each of the driven shafts P for the two spuds H extends inwardly and downwardly into the hull, as plainly indicated in Fig. 1, and on the lower ends of each of the said 85 shafts P is secured a bevel pinion S in mesh with a bevel gear wheel S' secured to the shaft T' of an engine or other motor T, so that when the latter is running a rotary motion is given by the gear wheel S' and the 90 pinion S to the shaft P. If desired, a separate motor T may be employed and geared with a corresponding shaft P, so that either shaft P can be rotated independently of the other if desired, as indicated in Fig. 4. 90

When the shaft P is driven then the worm O' imparts a rotary motion to the worm wheel O, thereby driving the shaft L' so that the pinion L in mesh with the rack K moves the lower spud section H² upward or 95 downward on the upper spud section H' according to the direction in which the shaft P is turned at the time. It is understood that after the lower spud section H² has been adjusted to the desired position, the 100 motor T is stopped and the spud section H² remains locked in the adjusted position by the worm O' engaging the worm wheel O. It is also understood that when the lower spud section H² is caused to slide up or down 105 on the upper spud section H', then the entire spud is caused to swing inward or outward owing to the connection of the spud H

with the shear B by the link J, and the bearing Q is free to swing on the shaft L' to avoid binding of the gearing. In practice, the lower spud section H² is raised or lowered about three or more feet.

From the foregoing it will be seen that by the arrangement described the spud can be readily adjusted to change the position of the dredge or other machine correspondingly, and to allow of quickly withdrawing the spuds from active position whenever it is desired to move the machine about from one place to another.

It is understood that the lower spud section H² can be readily moved downward on the upper spud section H' by the powerful mechanism described, so that the machine can be readily raised or its level changed.

It will also be noticed that when it is desired to move the dredge or similar machine about from one place to another, the lower spud section H² can be readily moved in the upper spud section H' so as to move the foot I off the ground without requiring swinging of the boom D and parts supported thereby from side to side in order to raise the spuds one at a time, as heretofore practised.

Having thus described my invention, I claim as new and desire to secure by Letters Patent:

1. A dredging or similar machine provided with spuds on opposite sides of the machine, each spud being made of an upper and lower section slideable one upon the other, the lower section being provided with a rack, a pinion mounted on the upper section and engaging the rack of the lower section, a worm wheel on the shaft of the said pinion, a worm carried by the upper spud section and meshing with the worm wheel, and a driven shaft upon which the worm is mounted to slide and with which said worm turns.

2. A dredging or similar machine provided with spuds on opposite sides of the machine, each spud being made of an upper and a lower section slideable one on the other, a rack on the lower section, a pinion in mesh with the said rack, a pinion shaft carrying the said pinion and journaled on the upper spud section, a worm wheel on the said shaft, a bearing mounted to swing on the said pinion shaft, a driven shaft, and a worm mounted to turn with and to slide on the said driven shaft, the said worm being carried by the said bearing.

3. A dredging or similar machine provided with spuds on opposite sides of the machine, each spud being made of an upper and a lower section telescoping one in the

other, a rack on the lower section, a pinion in mesh with the said rack, a pinion shaft carrying the said pinion and journaled on the upper spud section, a worm wheel on the said shaft, a driven shaft, a worm mounted to turn with and to slide on said driven shaft, said worm being mounted to swing, a motor on the machine, and a gearing connecting the motor shaft with the said driven shaft.

4. In a dredge or similar machine, a hull, shears mounted on the hull, spuds each formed of an upper and a lower section slideable one on the other, the upper section having its upper end pivoted to the upper end of the shears and the lower section having a rack, a pinion mounted on the lower end of the upper section and meshing with the rack of the lower section, a driven shaft, and gearing for operating the pinion from the driven shaft, the member of the gearing carried by the shaft being slidably mounted thereon.

5. In a dredge boat, in combination a deck, an upright frame mounted on said deck, a pair of spuds pivotally connected to said frame, each spud comprising a supporting arm and an extensible arm fitted in telescopic relation to said supporting arm, means to extend and retract said extensible arm mounted at the end of said supporting arm from which said extensible arm extends, power means mounted on said deck, and an extensible shaft having connections with said first mentioned means and said power means, one of said connections comprising a pivoted bearing whereby the extensible arm may be extended or retracted at different angular positions of said spud.

6. In a dredge or similar machine, a hull, a frame mounted on the hull, spuds each formed of an upper and a lower section slideable one on the other, the upper section having its upper end pivoted to the upper end of the frame and the lower section having a rack, a pinion mounted on the lower end of the upper section and meshing with the rack of the lower section, power means on the hull, a driven shaft connecting said power means and said pinion in swinging and sliding relation whereby said driven shaft will be operative in different angular positions of said spud.

In testimony whereof I have signed my name to this specification in the presence of two subscribing witnesses.

EARL W. DOTTON.
